M. J. WILLIAMS

SUPPORT

Filed Sept. 17, 1925

Inventor
Myrl J. Williams
By George D. Aight
Hes. G. Aight

UNITED STATES PATENT OFFICE.

MYRL J. WILLIAMS, OF CHICAGO, ILLINOIS, ASSIGNOR TO THE WASHBURN COMPANY, OF WORCESTER, MASSACHUSETTS, A CORPORATION OF MASSACHUSETTS.

SUPPORT.

Application filed September 17, 1925. Serial No. 56,865.

This invention relates to improvements in supports.

One object of the invention is to provide a support for articles to be dried, such as towels, clothes, etc., including a plurality of arms on which the articles may be hung, a carrier on which the arms are swingingly supported on a common axis so that the same may either be folded against the carrier in an inoperative position, or projected to operative position, and a wall bracket on which the carrier is rotatably adjustable to dispose the axes on which the arms swing in either a horizontal or a vertical position wherein the carrier is displaceable laterally on the bracket so that the carrier may be shifted during adjustment to clear an obstruction, such as a ledge, an adjacent projecting wall portion, or an adjacent wall at the corner of a room.

Another object of the invention is to provide a support of the character indicated, including a holder carrying a plurality of hinged arms adapted to support articles thereon, wherein the holder is adjustable and is adapted to be locked in position to bring the arms into operative relation, and is further adjustable to another position so that the arms may be folded out of the way.

Still another object of the invention is to provide a support of the character indicated, of simple construction, comprising few parts and which may be cheaply and economically manufactured.

Other objects and advantages of the invention will more fully and clearly appear from the description and claim hereinafter following.

In the drawing forming a part of this specification, Figure 1 is a front elevational view of the improved support showing parts thereof in section. Figure 2 is a perspective view of the support, showing the article-supporting arms in pendent, inoperative position. Figure 3 is a vertical, sectional view corresponding substantially to the line 3—3 of Figure 1, the horizontal position of the carrier being shown in full lines and the vertical position of the same being indicated in dotted lines. Figure 4 is a horizontal, sectional view corresponding substantially to the line 4—4 of Figure 3, showing the support applied in the corner of two adjacent walls of a room.

The improved support, as shown, comprises

broadly, a bracket A adapted to be secured 55 to a wall; a carrier B mounted on the bracket and a plurality of swingingly supported arms D—D on the carrier.

The bracket A is in the form of an elongated, dished plate-like member having openings 10—10 at the top and bottom thereof adapted to receive screws or other fastening devices by which the bracket is secured to a wall or any other support. At the center, the plate A is provided with a pivot member 60 65 11 in the form of a short rivet having an enlarged head 12. The shank of the rivet is reduced at the inner end, as indicated at 13, the reduced portion being accommodated in a suitable opening in the plate A and the free 70 end of the rivet being upset as indicated at 14. The plate A is also provided with a locking element 15 in the form of a rivet disposed above the pivot member 11. The locking element 15 is in all respects similar to 75 the member 11 hereinbefore described, having an enlarged head 16 and being secured to the plate A by having the inner end thereof upset as indicated at 17.

The carrier B is in the form of a U-shaped bar, having a main body portion 18 and a pair of outwardly projecting arms or lugs 19 at the opposite ends thereof. The main body portion 18 of the bar B is provided with an elongated central opening 20 adapted 80 85 to slidably receive the pivot member 11. It will be evident that the carrier B is thus rotatably, adjustably mounted on the bracket A and is also laterally movable thereon, the opening 20 and the pivot member 11 providing a lost motion connection between the supporting plate and the carrier B. The main body portion 18 of the carrier B is provided with a pair of L-shaped locking recesses 21—21 adjacent the opposite ends and 90 opening through the same side edge thereof. The elongated portion of each L-shaped recess extends parallel to the longitudinal axis of the member 18. As most clearly shown in Figures 1 and 2, the walls at the entrance 100 to the openings 21 are rounded off as indicated at 22 and 23 to facilitate entering the locking member 15 within the corresponding opening. The free ends of the arms 19 are provided with alined openings adapted to 105 receive a pivot pin 24 on which the arms D are swingingly supported. As herein illustrated, the arms D are preferably three in

number, and may be of any suitable design. The arms D are independently rotatable on the pin 24 and may be adjusted to different angular positions with reference to each other so as to provide spaced members on which the articles to be dried may be hung.

In using my improved support, the bracket is secured to a vertically disposed wall in the position shown in Figures 1 and 10 2. It will be evident that with the carrier disposed in the horizontal position shown in these two figures, the arms D will assume a pendent position in which they will be folded out of the way against the wall. In 15 order to bring the supporting arms D to operative position, the carrier B is rotated about the pivot 11 until one of the locking recesses 21 is brought into registration with the locking element 15. After the element 15 20 has been entered within one of the recesses 21, the carrier is slid a slight distance in order to engage the locking element 15 in the elongated straight portion of the recess 21 and lock the carrier B in vertical position. It will be evident that the carrier may be rotated either in a right hand or left hand direction to effect engagement of the locking element 15 with either of the recesses 21. By providing the elongated opening 20 in which the pivot member 11 works, the necessary sliding movement for permitting locking engagement of the pin 15 with the corresponding locking recess 21 is permitted. In this connection, it is pointed out 35 that the elongated recess 20 is made of sufficient length to permit of lateral shifting of the carrier B on the plate A to such an extent that the carrier will clear any obstruction which may be presented adjacent either 40 side of the supporting plate A. By this arrangement, my support is particularly adapted for use in confined places, such as corners of rooms, or on walls that have projecting portions. Figure 4 illustrates the 45 support applied in the corner of a room. As shown in this figure, the carrier B may be shifted to one side so as to clear the adjacent wall and permit the carrier to be

swung on the plate A without coming into contact with said wall.

It will be evident that I have provided a support for articles to be dried which is of extremely simple construction and which may be cheaply and economically manufactured. By providing a carrier which is formed from a straight bar, having the opposite ends thereof bent up at right angles to provide a U-shaped member, the cost of manufacture of this element is greatly reduced and a substantial saving in material 55 effected. A series of carriers may be cut from a single bar, it being merely necessary to provide the bar with openings 20 and locking recesses 21 at intervals and severing the bar into proper lengths to provide the proper number of carriers. After the bar has been severed into lengths, the opposite ends of each section are bent at right angles thereto to provide the pivot pin receiving 60 arms or lugs.

While I have herein shown and described what I now consider the preferred manner of carrying out my invention, the same is merely illustrative, and I contemplate all changes and modifications that come within 75 the scope of the claim appended hereto.

I claim:

In a support, the combination with a bracket; of a U-shaped bar; a plurality of swinging arms disposed between the free end members of said U-shaped bar, the main body portion of the bar having an elongated, longitudinally disposed central opening and a pair of locking recesses extending inwardly from one side edge thereof; a pivot member fixed to the bracket and slidably accommodated in said elongated opening of the bar; and a locking lug on said bracket adapted to be engaged in either of said locking recesses of the bar to lock the 80 latter to the bracket.

In witness that I claim the foregoing I have hereunto subscribed my name this 9th day of September, 1925.

MYRL J. WILLIAMS.
